DESIGN FOR A REFUSE RECEPTACLE OR SIMILAR ARTICLE

Russell C. Hol slag, Brooklyn, N. Y.

Application October 28, 1941, Serial No. 103,916

Term of patent 7 years

To all whom it may concern:

Be it known that I, Russell C. Hol slag, a citizen of United States, residing at Brooklyn, in the county of Kings and State of New York, have invented a new, original, and ornamental Design for a Refuse Receptacle or Similar Article, of which the following is a specification, reference being had to the accompanying drawing, forming part thereof.

In the drawing, the figure is a perspective view of a refuse receptacle or similar article, showing my new design.

The receptacle shown is circular in cross-section throughout its length.

The characteristic feature of my design resides in a refuse receptacle of the configuration shown having a top edge curved in the specific manner illustrated.

I claim:

The ornamental design for a refuse receptacle or similar article, substantially as shown and described.

RUSSELL C. HOLSLAG.
